METHOD OF LOCATING INTERSTRAND
SHORT CIRCUITS IN STRANDED ARMA-
TURE BARSRobert F. Edgar, Pattersonville, N. Y., assignor to
General Electric Company, a corporation of
New York

Application February 1, 1950, Serial No. 141,808

1 Claim. (Cl. 175—183)

1

This invention relates to improved method for detecting and locating interstrand short circuits in stranded armature bars.

Armature bars for large dynamo-electric machines are stranded to reduce eddy currents within the bar. Light insulation separates the strands, and heavy insulation surrounds the entire bar. The strands are soldered together at the ends so that each bar is a stranded conductor. If a short circuit exists between strands, eddy currents may flow through the shorted strands sufficient to cause heating at the short circuit which may eventually damage the insulation of the armature bar and cause failure of the dynamo-electric machine. Therefore, it is important to locate the interstrand short circuits before such trouble develops.

In the manufacture of stranded armature bars, it is customary to test the bar for interstrand short circuits before the strands are soldered together at their ends by applying voltage between each strand and all of the other strands. When it is discovered in this way that two strands are shorted together somewhere in the bar, it is desirable to have some method for quickly locating the exact position of the short circuit within the bar without further damaging the insulation. If the short circuit can be so located, it may be possible to open the bar at this point and correct the trouble, and thus avoid scrapping the defective bar.

An object of this invention is to provide improved means for locating an interstrand short circuit within an armature bar without further damage to the insulation.

After the initial test for interstrand short circuits, the ends of the strands are soldered together and the heavy outer insulation is applied to the bar. During this process, additional interstrand short circuits may develop.

Another object of this invention is to provide means for detecting and locating short circuited strands within an armature bar after the strands are soldered together at their ends.

Other objects and advantages will appear as the description proceeds. The features of this invention which are believed to be novel and patentable are pointed out in the claim which forms a part of this specification.

For a better understanding of the invention, reference is made in the following description to the accompanying drawings, in which Fig. 1 is a plan view of a portion of an armature bar and apparatus for locating interstrand short circuits within the bar; Fig. 2 is a section along the line

2—2 of Fig. 1; Fig. 3 is an elevation showing the relative position between the armature bar and the test apparatus at a later stage in the location of a short circuit; Fig. 4 is a schematic diagram of apparatus for detecting and locating interstrand short circuits after the ends of the strands have been soldered together; Fig. 5 is a partial section along the line 5—5 of Fig. 4, drawn to a larger scale; and Fig. 6 is a graph of voltage variations hereinafter more fully explained.

Referring now to Figs. 1 and 2, a large armature bar 1 comprises a plurality of strands 2 which are insulated one from another by insulation 3. Assume that strands 2' and 2'' have been found 5 to be short circuited somewhere within the bar. It is desired that this short circuit be located so that the bar may be repaired. Location of the short circuit is complicated by the fact that the strands do not run straight through the bar, but 10 are transposed to reduce circulating currents.

An oscillator 4 is connected to apply alternating current to the short circuited strands through a current limiting resistor 4'. The oscillator may have an output of 100 volts at 2000 cycles per 15 second, for example. Current limiting resistor 4' may be in the order of 2000 ohms. With this arrangement, the maximum power which can be supplied to the short circuit is less than 2 watts, which is not sufficient to produce further damage 20 in the insulation.

A magnetic member 5 is slightly longer than the width of the armature bar, as shown. At each end of member 5 and perpendicular thereto is a short leg 6, also of magnetic material. Member 5 and legs 6 form a U-shaped magnetic core adapted to fit loosely over the armature bar, as illustrated in Fig. 2. Upon each leg 6 there is a search coil winding 7. Attached to member 5 by bracket 8 is an electrical indicating instrument 9. A handle 10 may be provided for convenience in moving the magnetic core along the length of the armature bar.

Windings 7 are connected in series bucking relation to the input of an amplifier 11. The output of amplifier 11 is connected to indicating instrument 9, so that the indicating instrument reads the difference between the values of voltages induced in coil 7. The amplifier may conveniently be located in a separate case and connected to the search coils and to the indicating instrument through suitable cables. Since coils 7 are connected in series bucking relationship, any magnetic flux which travels the entire length of the U-shaped core induces equal and opposite voltages in the two search coils, and, therefore,

does not affect the indication of instrument 9. Current flowing through shorted strands 2' and 2'', however, produces flux traveling in opposite direction through the two search coils, and thus induces in the coils voltages which add to provide an indication at instrument 9. The location of instrument 9 directly above member 5 permits easy operation by a single operator.

Referring to Fig. 2, assume that the instantaneous current in strand 2' is flowing into the drawing, as indicated by the arrow tail (+), and that the instantaneous current in strand 2'' is flowing out of the drawing, as indicated by the arrow head (○). This current produces magnetic flux along the broken lines 12 and 13. It can be observed that this flux flows into both ends of the U-shaped magnetic core, and out near the center of the core, thereby inducing in windings 7 voltages which add together to produce an indication at instrument 9.

The short circuit between strands 2' and 2'' is located by placing member 5 across the armature bar at the end of the bar to which oscillator 4 is connected. The current through these short circuited strands produces an indication at instrument 9, as has been explained. Member 5 is moved along the length of the bar until the indication provided by instrument 9 suddenly decreases. This decrease in indication shows that short circuit current is no longer flowing through the bar immediately below member 5. Therefore, the location of the interstrand short circuit must be somewhere in the bar below member 5 in the position at which the sudden decrease in instrument reading occurs.

To locate the short circuit across the width of the armature bar, member 5 is lifted from the bar and the surface of the bar is explored with one of the coils 1, as illustrated in Fig. 3. Maximum indication of instrument 9 occurs when the coil 7 is directly over the interstrand short. The armature bar may then be opened at this point and the trouble repaired.

After the ends of the strands have been soldered together, the detection and location of short circuits may be accomplished in the following manner: Referring to Fig. 4, a completed armature bar 14, which is to be tested, is placed within the slot of a slotted magnetic fixture 15. Fixture 15 may be made of stacked laminations to simulate an armature slot in a dynamo-electric machine. Alternating magnetic flux is provided across the slot of fixture 15 by a second armature bar 16, placed at the bottom of the slot, through which 500 amperes or more of alternating current is provided through connections 17. It will be appreciated that other means, such as a winding, may be employed to provide the magnetic flux across the slot. The two ends of the armature bar 14 are explored simultaneously with similar test coils 18 and 19, respectively. The construction of the test coils is more clearly shown in Fig. 5.

Referring now to Fig. 5, test coil 18 comprises an E-shaped magnetic core 20 and two windings 21 and 22 upon opposite sides of the magnetic core. Windings 21 and 22 are connected in series bucking relation so that any external magnetic field, such as the magnetic field produced across the slot of fixture 15, induces equal and opposed voltages in the two windings. These voltages cancel, so that the net output of search coil 18 is zero.

Assume that an interstrand short circuit exists between strands 23 and 24, somewhere within the armature bar. The alternating magnetic flux

across the slot of fixture 15 causes circulating currents to flow through the short circuited strands. The instantaneous direction of this current in strand 23 may be into the drawing, as indicated by the arrow tail (+), and the current in strand 24 may be out of the drawing, as indicated by the arrow head (○). These currents produce magnetic flux along the paths indicated by broken lines 25 and 26. When the center leg of core 20 is between the two short circuited strands, as illustrated in Fig. 5, the flux produced by circulating short circuit currents travels in opposite directions through windings 21 and 22, so that the voltages induced in the two windings by this flux add together and produce a net output voltage from the search coil. The magnetic flux produced by circulating short circuit current is in phase quadrature to the flux across the slot of member 15, and, therefore, the voltage induced in the search coil by the short circuit currents is in phase with the flux across the slot.

Due to imperfect transportation of the strands, or to other reasons, circulating currents may be produced in strands which are not short circuited. These circulating currents also produce magnetic flux which induces in the search coils voltages which are in phase with the magnetic flux across the slotted member 15. These circulating currents might produce short circuit indications if only one search coil were used. Such voltage indications are eliminated by using two search coils 18 and 19, as shown in Fig. 4, connected in series bucking relation. The two search coils 18 and 19 are moved simultaneously by equal amounts across the respective ends of armature bar 14, so that the two search coils are always adjacent to the opposite ends of the same strands. Circulating currents in strands which are not short circuited must flow in the same direction at both ends of the armature bar. Therefore, the voltages produced in the search coils by these circulating currents are opposed and cancel out. On the other hand, circulating currents in short circuited strands flow in opposite directions at the respective ends of the armature bar. Therefore, these currents cause voltages to be induced in the two search coils which add and produce an indication of a short circuit. A compensating network comprising capacitors 27 and 28 and tapped resistors 29, 30 and 31, connected as shown, may be provided to balance any dissimilarities in the characteristics of the two search coils.

The net voltage from the two search coils is applied to a phase selective indicating circuit which may comprise a triode 32, rectifiers 33 and 34, and voltmeter 35. The net voltage from the search coils is applied between grid and cathode of triode 32 through connections 36 and 37 and capacitor 38. A grid leak resistor 39 and a bias voltage source 40 may be provided to maintain the proper bias potential at the grid of triode 32. The plate of triode 32 is connected to the center of a voltage divider comprising resistors 41, 42 and 43 connected in series between the cathodes or rectifiers 33 and 34. Voltmeter 35 is also connected between the cathodes of the two rectifiers. The anodes of the rectifiers are connected to opposite ends of the secondary winding of a transformer 44. The primary winding of transformer 44 may be connected to the secondary winding of another transformer 45 through a phase adjusting network comprising capacitor 46 and variable resistor 47. The primary winding

of transformer 45 may be connected through another transformer 48 to the alternating current supply connections 17. Transformer 48 is a current transformer having a loading resistor 49 connected across its secondary winding. The current through resistor 49, and the voltage across this resistor are in-phase with the current in the bar 16 and, therefore, in-phase with the flux across the gap of fixture 15.

Rectifiers 33 and 34 conduct current alternately, as in a conventional full-wave rectifying circuit. When the potential at the grid of triode 32 is the same during both half cycles of the supply current, rectifiers 33 and 34 conduct equal amounts of current, and the indication of voltmeter 35 is zero. When there is a difference in the triode grid potential during the two half cycles, the rectifiers conduct unequal currents, and the resulting difference between the respective voltage drops across resistors 41 and 43 causes a voltage indication by the voltmeter. Voltmeter 35 thus indicates the value of in-phase alternating potential applied to the grid of triode 32, and furthermore the polarity of the voltmeter indication shows the phase reversals of this potential. Voltages which are in phase quadrature to the supply current produce no indication at voltmeter 35. The phase of current supplied to the rectifiers may be adjusted for best operation by adjusting the value of resistor 47.

Curve 50, Fig. 6 is a graphical representation of the voltmeter indications plotted as a function of the position of search coils 18 and 19 across the width of armature bar 14. At point 51 a large negative indication of the voltmeter is obtained. Such an indication shows that at this point the search coils are adjacent to short circuited strands in the armature bar. These strands may be marked, and the armature bar then removed from the test fixture. The solder at the ends of the short circuited strands may

be removed, and the short circuit may then be located within the bar in the manner described in connection with Figs. 1, 2, and 3.

Having described the principle of this invention and the best mode in which I have contemplated applying that principle, I wish it to be understood that the examples described are illustrative only, and that other means can be employed without departing from the true scope of the invention.

What I claim as new and desire to secure by Letters Patent of the United States is:

The method of locating interstrand short circuits in stranded armature bars, which comprises placing the armature bar within a slot in a slotted magnetic fixture so that the ends of the bar extend beyond the ends of said fixture, producing alternating magnetic flux across the slot in said fixture, whereby circulating electric currents are produced through short circuited strands of the armature bar, exploring both ends of the armature bar simultaneously with search coils, so that circulating currents through short circuited strands induce voltages in the search coils when adjacent to such strands which are in phase with the magnetic flux across said slot, said search coils being moved simultaneously by equal amounts across the width of the armature bar so that the respective coils are always adjacent to opposite ends of the same strands, and detecting the difference between values of such voltages induced in the respective coils.

ROBERT F. EDGAR.
